ENGINE STARTING DEVICE

Louis Weglein, Jr., Philadelphia, Pa.

Application July 3, 1935, Serial No. 29,625

8 Claims. (Cl. 185—39)

My invention relates to a new and useful engine starting device and it relates more particularly to a spring actuated starting device, in which a resilient element is utilized for storing energy 5 to be used at will.

My invention still further relates to a starting device of this character, including means for rendering it universally applicable to all engines which are conventionally started by a spinner 10 mechanism in which a rope or other flexible element is wound around a sheave wheel to crank such engines.

My invention still further relates to a novel construction in a starting mechanism which is 15 calculated to apply maximum torque with the least possible exertion and one which is of an extremely light construction, thus adding a minimum to the dead load of the engine.

My invention still further relates to a starting 20 device of the character described, which includes novel means for mounting said device with respect to the engine, in connection with which it is to be used, so as to render my starting device applicable to any type of support, and whereby the starting mechanism proper may be swung 25 into and out of operative position at will.

My invention still further relates to a starting 30 mechanism which is provided with effective safety devices to eliminate all chances of accidental injury to the operator.

My invention still further relates to a novel 35 means for anchoring the resilient element constituting the motive power of the starting device, whereby all danger of damage to the spring or the spring casing is entirely eliminated.

My invention still further relates to a novel 40 arrangement for automatically disengaging the spinner element of my starting device from the engine during the winding operation of the resilient element, and for automatically engaging the spinner element with said engine during the unwinding of the resilient element.

My invention still further relates to a starting 45 device which can be wound up while in engagement with a running engine without interfering with the operation of the latter, for subsequent instantaneous use when such engine shall have stopped.

My invention still further relates to various 50 other novel features of construction and advantage, all as hereinafter set forth in the following specification and the accompanying drawings in which:

Fig. 1 represents a plan view of a starting 55 mechanism embodying my invention.

Fig. 2 represents a side elevation of Fig. 1.

Fig. 3 represents an end elevation of Fig. 2 showing the starting mechanism applied to the engine, in full lines, and tilted away from the engine, in dotted lines.

Fig. 4 represents a section on line 4—4 of Fig. 1.

Fig. 4—A represents on a reduced scale a plan view of the top of the engine shown in Fig. 1 with the starting device removed and other parts omitted.

Fig. 5 represents a plan view of Fig. 4 with the cover of the casing removed.

Fig. 5—A represents a fragmentary plan view of one of the pauls seen in Fig. 5.

Fig. 6 represents a plan view of Fig. 5 with the 15 winding mechanism removed and certain other parts omitted.

Fig. 7 represents a bottom plan view of the starting mechanism before it is applied to the engine certain parts being omitted.

Fig. 8 represents a plan view of an adapter 20 plate forming part of my invention.

Fig. 9 represents a section on line 9—9 of Fig. 7.

Fig. 9—A represents a section similar to Fig. 9 showing a modified construction.

Fig. 10 represents a plan view on an enlarged 25 scale of one of the pauls seen in Fig. 5, shown detached.

Fig. 11 represents a section on line 11—11 of Fig. 10.

Fig. 12 represents a section on line 12—12 of Fig. 1.

Fig. 13 represents a section on line 13—13 of Fig. 12.

Fig. 14 represents a perspective view on an 35 enlarged scale of a part of the fastening strip used in securing the starting device to the gas tank of the engine or other support.

Referring to the drawings in which like reference characters indicate like parts, and more 40 particularly to Fig. 4, it will be seen that my novel starting mechanism comprises an upper section 1 adapted to contain the resilient element 2, which is in the form of a spring and lower section 3, which carries means adapted to engage the fly 45 wheel 4, or other cranking device of an internal combustion engine, not shown. The spring 2 is anchored at its outer end to the post 6 and its inner end is hooked as at 7 detachably to engage the cam-faced teeth 8 of the ratchet 9. The teeth 50 8 of the ratchet 9 are so arranged that, when the ratchet is turned counter-clockwise, the hooked end 7 of the spring 2 will engage the ratchet as shown in Fig. 6, and so that, after the spring 2 is unwound, the inner end 7 of the spring will ride 55

freely over the cam faces of the teeth 8 of the ratchet 9. By this arrangement, which leaves the inner end 7 of the spring 2 free after the unwinding of the spring, all danger of the breakage of 5 the spring, due to violent backlash, is entirely eliminated. In order to enable me to make the spring-enclosing casing 1 of relatively thin cross section, in the interest of lightness and economy, I provide the reenforcing ribs 11, which extend 10 sufficiently along the casing wall on either side of the post 6 in order to guard against fatiguing or breaking of the casing 1 along the section indicated, under the impact of the unwinding operation of the spring. Fitting within the annular 15 wall of the casing 1, and completely covering the spring 2, is the plate 13 through a central opening in which, the stem 14 of the ratchet 9 projects. The plate 13 is provided with the lugs 15, which are provided with holes registering with corresponding holes in the annular wall of the casing 1, to receive the screws or other fastening means 16. The plate 13 is also preferably provided with a hole 17 in one of the lugs 15, to receive the upper end of the post 6, thereby to guide and key 20 the plate 13 with respect to the entire assembly. One of the lugs 15 is also preferably provided with a bottom extension (not shown) which engages the opening 18, further to lock the plate 13 to the assembly of the upper section 1. The upper end 25 of the stem 14, of the ratchet 9, is provided with the square portion 19 which engages a corresponding square hole in the center of the ratchet wheel 20, so that, the turning of the ratchet wheel 20 will result in the turning of the ratchet 30 9, the engagement of the inner end 7 of the spring 2 with one of the teeth 8 of the ratchet 9, and the consequent winding of the spring 2. In order to turn the ratchet wheel 20 and thus wind the spring 2, I provide the pinion 22, which is provided with the polygonal socket 24, adapted to receive the corresponding shaped end 25 of the crank 26. In order to retain the ratchet wheel 20 against unwinding, I provide the dogs or pauls 28 and 30, which are normally pressed against the 35 teeth of the ratchet wheel 20 by the flat springs 32, as best seen in Fig. 5. Secured to the section 1, in any suitable manner, and fitting over the plate 13, and the parts carried thereby, is the cover plate 35 which is provided with the hub 36 which 40 forms a bearing for the upper end of the stem 14, and which is also provided with the opening 38 registering with and adapted to receive the socket 24 of the pinion 22 and, with the openings 40 and 42, which register with and receive the 45 square sockets 43 of the pauls 28 and 30. In order to wind the spring 2, the end 25 of the wrench 26 is inserted through the opening 38 to engage the socket 24 and turn the pinion 22, engaging the ratchet wheel 20, which engages the inner end of 50 the spring. In order to permit the spring 2 to unwind, the wrench 26 is disengaged from the pinion 22 and the end 25 thereof, is inserted through one or the other of the openings 40 or 42, to disengage either of the pauls 28 or 30, leaving the other of the pauls still holding the ratchet 55 20 against rotation. With one of the pauls disengaged, the other paul is then also disengaged, whereupon, the ratchet wheel 20 is free to rotate and thus permits the spring 2 to unwind freely. 60 The pauls 28 and 30 are provided with the circular flanges 41 which overhang the flat springs 32 to retain said springs in position. When either of the pauls 28 or 30 is turned into the "off" position (see Fig. 1), it will assume and remain in 65

the position shown in Fig. 5—*a*, due to the pressure of the spring on the stem of the paul, and in which the paul clears the teeth of the ratchet wheel 20, so that the latter is free to rotate. The stem 14 projects downwardly through the hub 45 5 of the lower section 3 and is rigidly secured to the lower section 3 so that, when the ratchet 9 is turned, the section 3 will turn with it, whether the turning is due to the winding or unwinding of the spring 2. On the top of the engine is provided 10 any suitable hub or socket 44 which forms a journal for the lower end of the stem 14 and which aids in centralizing the starting device with respect to the engine. In the pendant, annular wall of the lower section 3, I provide the loosely pivoted 15 trailing pauls 48, which have the lower hooked ends 49, which register with the openings 46, in the sheave wheel 47, of the fly wheel 4 of the engine. In Fig. 4—*A* I show the conventional rope-engaging openings 46, which are enlarged at their 20 outer periphery to release the knot in the conventional spinning rope. When the casing 3 is turned in a counter-clockwise direction, during the winding of the spring 2, the trailing pauls 48 will ride over, but will not engage the openings 46, but 25 when the casing 3 is turned in a clockwise direction, during the unwinding of the spring 2, the hooked ends 49 of the trailing pauls 48, will engage the openings 46, and thus turn the fly wheel 30 of the engine. The sheave wheel 47, illustrated, is provided with the customary groove 50, which is adapted to receive the conventional starting rope, which can be used in the usual manner independently of my starting mechanism, or in the absence of the latter. While the trailing pauls 48 35 are adequate for use in the horizontal position, it is obvious that they will not work satisfactorily in a vertical position, and for that purpose I have provided the auxiliary holes 52 which are adapted to receive the spring pressed pauls 53, best seen 40 in Fig. 9—*A*. The spring pressed pauls 53 are also provided with the bottom hooked ends 54, which are deflected away from the openings 46, so that, they will not engage the holes when the casing 3 is turned in counter-clockwise direction, 45 but so that they will engage said holes when the casing 3 turns in a clockwise direction during the unwinding of the spring 2. The use of the pauls 48 or 53 is optional according to the vertical or horizontal position of the sheave wheel 47. In 50 order to mount my starting device conveniently, I have provided a novel arrangement which consists of the cross bar 60 which is provided with the arms 61, which have the threaded bosses 62 which are adapted to engage the wing bolts 63. 55 Cooperating with the cross bar 60 is another cross bar 65, which carries the lugs 66 which are open, as at 67, to receive the shank of the wing bolts 63. The outer ends of the cross bar 65 are knurled or serrated to receive and engage the correspondingly knurled ends 70 of the clamps 71, the bottom ends of which are adapted to engage the ends of the bottom strap 72. The ends of the bottom strap 72 are provided with the vertical flanges 73 which bear against the clamps 71, and are also provided with the seats 75 to receive and engage the ends of the bolts 76, which pass through the threaded bosses 77 at the lower ends of the clamps 71. The strap 72 is made of two or more sections 60 which are stapled together, as at 79, to permit adjustment of the length of the strap to the size of the gas tank 80 of the engine, or other support to which the starting device may be secured, it being understood that the strap 72 is not only 70 75

adjustable, but is also flexible to permit it to conform to the contour of the gas tank or other support 80. Extending from the cross bar 65 is a leather strap or other cushioning device 82, which 5 forms a cushioned support for the starting device when the latter is tilted off the motor on to the gas tank or other support 80 as shown in Fig. 3. It will be understood that when the starting device is tilted, it pivots about the shank of the wing bolts 63 in the lugs 66, as best shown in Fig. 3. If desired, I may utilize a packing 18x which is 10 preferably positioned between any two adjacent reinforcing ribs 11 to form an adjustable bearing for the spring 2, as best seen in Fig. 6. The 15 deflection of the vertical flanges 13 of the strap 12 into the position shown above in Fig. 14 leaves the projecting ends 14 between which the clamps 71 are engaged, as best seen at the bottom of Fig. 2, whereby added firmness and strength is 20 imparted to the clamping arrangement by which the starting device is secured to the gas tank or other support 80. In order to render my starting device applicable to any internal combustion engine, other than that illustrated in 25 Fig. 1, that is, one in which the sheave wheel 47 with the openings 46 thereof is omitted, I utilize the adapter plate 84 (shown in plan in Fig. 8) which is suitably secured to the fly wheel, or other cranking mechanism of such an internal combustion 30 engine, the holes 85 in the adapter plate 84 serving to engage the pauls 48 or 53 in exactly the manner hereinabove described in connection with the construction illustrated. In Figs. 2 and 4, I have shown the pauls 48 in engagement with 35 the holes 46 in the sheave wheel 47, and in Fig. 3, I have shown the pauls 48 out of engagement with the holes 46. The clamps 71 may each be made of one piece, or they may be made of two sections secured together by any fastening devices 88 en- 40 gaging the spaced holes 90 whereby the clamps 71 can be adjusted for engagement with gas tanks or other supports 80 of different sizes. While I have shown one form of adjustable clamps 71, it is to be understood that any other form of adjustment 45 can be used.

The operation is as follows:

The starting unit is tiltably and adjustably secured to the cranking element 4 of an engine (see Figs. 2 and 3) by the parts 10, 11, 12, 13 and their 50 adjuncts. By means of the socket wrench 26 the shaft 24 is engaged and turned to wind the spring 2. During the winding of the spring 2 the free inner-end 1 thereof engages one of the teeth 8 of the ratchet 9, but when the spring 2 is unwound 55 the end 1 thereof at once disengages from the ratchet 9 thus preventing the breaking of the spring due to violent back-lash. During the unwinding of the spring the pauls 28 and 30 are set to engage the gear 20 to prevent unwinding. The 60 unit is wound up and put in the tilted position shown in Fig. 3, or away from the engine. When it is desired to start the engine, it is merely necessary to bring the starting device from the position shown in dotted lines in Fig. 3 to the position 65 shown in solid lines in Fig. 2 to engage the intermediate revoluble element 3, which in turn has the pauls 48 or 53 which, when the spring 2 is unwound, will engage the cranking element. In order to release the spring, and crank the engine, 70 the socket-wrench 26 first engages one or the other of the square-shafts 43 to disengage one of the pauls 28 or 30 from the gear 20, whereupon the spring 32 bearing upon the corresponding cam 41 will retain the dog or paul 28 or 30 in its disengaging position (shown in Figs. 5 and 8). With

one of the pauls thus disengaged, the socket-wrench is then removed and engaged with the other square-shaft 43 in order to disengage the other paul which is also provided with a retaining spring whereupon the spring is unwound and the 5 engine is cranked.

By means of the two pauls 28 and 30 I provide for extreme safety since, while it may be possible accidentally to disengage a single paul, it will certainly take positive and deliberate action to dis- 10 engage both.

In order to render my device adaptable to all engines I utilize the adapter plate, shown in Fig. 8, which may be suitably secured to the cranking element of any engine regardless of the shape or 15 position of said cranking element, and which has the holes 85 calculated to engage the pauls 48 or 53 carried by the revoluble element 3. It will further be seen that, if one of the pauls 48 or 53 breaks, it is merely necessary to remove the re- 20 taining cutter-pin and put another one in its place without the aid of a mechanic, and only at the cost of the price of a paul.

Having thus described my invention, what I claim as new and desire to secure by Letters Pat- 25 ent is:

1. The combination with a starting device for an internal combustion engine of means for detachably and tiltably fastening said starting device in proximity to said engine whereby said 30 starting device may be brought into or out of operative position with respect to said engine.

2. The combination with a starting device for an internal combustion engine of adjustable means for detachably and tiltably fastening said 35 starting device in proximity to said engine, whereby said starting device may be brought into or out of operative position with respect to said engine.

3. The combination with a starting device for 40 an internal combustion engine of means for detachably and tiltably fastening said starting device in proximity to said engine, whereby said starting device may be brought into and out of operative position with respect to said engine, and 45 means for cushioning said starting device in its tilted position away from said engine.

4. The combination with a starting device for an internal combustion engine having pauls for 50 engaging the cranking element of said engine of an adapter plate adapted to be secured onto the cranking element of said engine and having holes therein adapted to engage said pauls during the operation of said starting device.

5. A starting device for an internal combustion 55 engine comprising a casing, a spring inclosed in said casing, a ratchet adapted to be engaged by the inner end of said spring during the winding operation thereof, and to be disengaged from the inner end of said spring after the spring is com- 60 pletely unwound to prevent breakage of said spring due to the violent backlash which invariably follows the sudden release of the energy stored in said spring.

6. A starting device for an internal combus- 65 tion engine comprising a casing, a spring inclosed in said casing, a ratchet adapted to be automatically engaged by the inner end of said spring during the winding operation thereof, and to be automatically disengaged from the inner end of 70 said spring after the spring is completely unwound to prevent breakage of said spring due to the violent backlash which invariably follows the sudden release of the energy stored in said spring.

7. A starting device for an internal combus- 75

tion engine comprising an upper fixed casing, a
spring therein, means for winding said spring, a
ratchet element detachably engaging the inner
end of said spring and freely rotatable with re-
spect to said upper casing, a lower revoluble section
5 rigidly secured to the lower end of said ratchet,
means carried by said lower revoluble section for
engaging the cranking element of said engine only
during the unwinding of said spring, and inde-
pendently operable safety devices for preventing
10 the accidental unwinding of said spring.

8. A starting device for an internal combus-
tion engine comprising an upper fixed casing, a

spring therein, means for winding said spring, a
ratchet element detachably engaging the inner
end of said spring and freely rotatable with re-
spect to said upper casing, a lower revoluble section
5 rigidly secured to the lower end of said ratchet, means carried by said lower revoluble
section for engaging the cranking element of said
engine only during the unwinding of said spring,
independently operable safety devices for pre-
venting the accidental unwinding of said spring,
10 and means for retaining each of said safety de-
vices in its operative or its inoperative position.

LOUIS WEGLEIN, JR.
